(No Model.)

J. H. & W. B. HUBBARD.

SIDING OR WEATHER BOARDING GAGE.

No. 372,221.

Patented Oct. 25, 1887.

UNITED STATES PATENT OFFICE.

JOHN HENRY HUBBARD AND WILLIAM BRANSON HUBBARD, OF GREENVILLE, ILLINOIS.

SIDING OR WEATHER-BOARDING GAGE.

SPECIFICATION forming part of Letters Patent No. 372,221, dated October 25, 1887.

Application filed April 29, 1887. Serial No. 236,575. (No model.)

To all whom it may concern:

Be it known that we, JOHN HENRY HUBBARD and WILLIAM BRANSON HUBBARD, citizens of the United States, residing at Greenville, in the county of Bond and State of Illinois, have invented new and useful Improvements in Siding or Weather-Boarding Gages, of which the following is a specification.

Our invention relates to improvements in siding or weather-boarding gages; and it consists in a certain novel construction and arrangement of parts for service, fully set forth hereinafter, and specifically pointed out in the appended claims.

15 In the drawings hereto annexed, Figure 1 is a view showing the manner of using the device. Fig. 2 is a detail perspective view of the same. Fig. 3 is a central longitudinal section. Fig. 4 is a transverse section on the line $x-x$ of Fig. 3.

Referring by letter to the drawings, A designates the body of the gage, having a longitudinal slot, B, therein, and a ring or finger-hold, C, at the lower end to facilitate the handling 25 of the tool.

D represents a slide, having a groove, d , therein to receive and slide on the rear side of the body, and E is the support or block on the rear side of the said slide, and having a bolt, 30 F, formed integrally therewith, extending through an opening, f , in the said slide, and also through the slot B. The outer end of the bolt F is threaded to receive the thumb-nut G, to bind the said bolt, and consequently the 35 slide and support carried thereby, at any desired point in the length of the slot B.

H represents a rearwardly-projecting plate or bracket secured on the lower end of the body of the gage, having an upturned end, 40 I, to be passed up in rear of the last-nailed board, and K represents a leaf pressure-spring secured to the rear side of the body, and adapted to bind the lower edge of the said last-nailed board against the said upturned end or 45 vertical arm of the bracket H.

To place the device in position for use, pass the vertical arm I in rear of the last-nailed board, depressing thereby the lower end of

the spring K, and the gage will be held rigidly in position, with the rear edge of the support 50 E pressed against the surface of the said last-nailed board. It will be seen that the distance between the upper side of the bracket and the upper side of the support E, on which the lower edge of the next board is rested, 55 will constitute the "weather" of the siding-board, and in order to enable the gage to be readily set to the desired weather or "showing," we provide a scale of inches on the side of the body and place an index on the edge of 60 the slide-bar D corresponding in position to the upper edge or side of the block or support.

It will be seen that when the gage is properly set in position, (one being placed at each end of the board,) and the board to be nailed 65 is placed in rear of the upper end of the slide-bar D, and resting at the lower edge on the upper side of the block E, the said board will be held securely in position, and may be nailed easily and accurately in place. 70

The device is strong, durable, neat, simple, and may be cheaply manufactured, and will be found very effective in use and a great saver of time, in addition to the fact that no 75 nails or pins need be driven into the face of the boards to support the next one above, the perforations made by the said nails marring the appearance of the completed work.

Having now described the construction, operation, and advantages of our improved 80 siding-gage, what we claim as new, and desire to secure by Letters Patent of the United States, is—

1. A siding-gage comprising the body A, having the slot B therein, the slide-bar D, 85 having the groove d , to receive the rear side of the body, and the aperture f , to align with the groove B, the support E, having an integral bolt, F, to pass through the aperture f and the slot B, and the thumb-nut G, to screw 90 on the threaded end of the said bolt, substantially as specified.

2. The improved gage herein described and shown, comprising the body A, having the ring C at its lower end and the slot B in its 95 upper end, the bracket H, having the up-

turned arm I secured to the lower end of the body, the spring K, secured to the rear of the body near its lower end, the slide D, fitted on the upper end of the body, the support E, carried by said slide and projecting through the slot B, and means for securing the slide at any desired point, substantially as specified. In testimony that we claim the foregoing as

our own we have hereto affixed our signatures in presence of two witnesses.

JOHN HENRY HUBBARD.

WILLIAM BRANSON HUBBARD.
